H. H. JOHNSTON

SYSTEM OF CONTROL

Filed Dec. 30, 1920

Fig. 1

UNITED STATES PATENT OFFICE.

HOWARD H. JOHNSTON, OF EDGEWOOD, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

Application filed December 30, 1920. Serial No. 434,076.

My invention relates to motor-control systems and it has particular relation to such systems as are employed in connection with railway cars.

5 The object of my invention is to provide an overload relay having simple means for adjusting the value at which it operates to meet varying requirements.

In the present system it is proposed to so 10 utilize the reset magnet of an overload relay that it may, in addition to its normal functions, operate to oppose the actuation of the relay by the overload magnet. In normal operation, the reset magnet is energized only 15 to restore the relay to its initial operative position. In case it is desired that the relay operate at a value above the normal value, the reset coil is connected in circuit through an interlock mechanism. When the relay is 20 actuated by an overload, the interlocking mechanism opens the circuit of the reset magnet coil. The reset magnet may then be employed to perform its normal function in restoring the relay to its closed position to complete the motor circuit.

25 My invention will be described in connection with the accompanying drawings, in which

30 Figure 1 is a side elevational view of the overload relay structure;

Fig. 2 is a view, in elevation, of the reset mechanism, and

Fig. 3 is a diagrammatic view of circuits and apparatus embodying my invention.

35 Referring to Fig. 1, an overload relay is provided with a stationary core member 1, an operating coil 2 and an armature 3. A plunger 4 is mounted concentrically with the core member 1. Contact discs 5 and 6 normally engage stationary contact members 7 and 8, respectively, when the armature 3 is in 40 its lower position and are disengaged when the armature is up. The armature 3 is latched in its upper position by a trigger 9. A reset magnet 11 is provided with an armature 12 for operating the trigger 9. The reset magnet 11 also controls the actuation 45 of the armature 3. An adjusting screw 10 acts as a stop or rest for armature 3 and also

serves to determine the initial air gap between core member 1 and the armature.

In order to restrict the operation of the armature 3 by the actuating coil 2, one end of the core 11a of the reset magnet is extended to form a pole piece 11b, the upper face of which is disposed to lie substantially parallel with a face 3a provided on the armature 3, when the latter is in its lower position. As shown, a bracket 10a is carried by the other end of the core 11a. Therefore, as will be observed, the reset magnet 11, with the pole piece 11a and bracket 11b, simulates a horseshoe magnet, which, with the armature 3 in the position shown in dotted lines in Fig. 1, forms a substantially closed magnetic circuit. Accordingly, when the magnet 11 is energized, it will oppose the operation of the armature 3 by the actuating coil 2.

The relay may be set to operate at either of two predetermined motor-current values.

The relay may be connected as shown in Fig. 3, wherein the operating coil 2 is in circuit with a motor armature 25 and the usual master controller 22. The operating coil 31 of a main-line contactor is controlled by relay contact members 5 and 7, which members are normally in engagement, by controller contact members 27 and 28, which engage on all running points of the controller, and by a control switch 16 which is normally positioned to the left, as viewed in the drawing. A snap switch 13 completes a circuit comprising reset magnet coil 14, a resistor 19 and the normally closed relay contact members 6 and 8; another circuit for this coil is established when switch 16 is actuated to the right.

Assuming a railway car operating on a fairly level track, snap switch 13 is open and the relay setting is fixed by the adjusting screw 10. It is also assumed that the operating coil 2 is properly designed for a known range of current values. The relay will be actuated to drop out line contactor 31 by the separation of contact members 5 and 7 in case the motor current rises above a predetermined value, for any reason, such as too rapid acceleration of the motor. A circuit

for the line contactor extends from positive line conductor 15, through control switch 16, when actuated to the left, contact members 27 and 28, conductor 29, relay contact members 5 and 7 and line contactor coil 31, to the negative line conductor 21. Switch 16 is actuated to restore the relay setting, as will be set forth later.

It is desirable on heavy grades, to raise 10 the setting of the overload relay and this is accomplished by means of the switch 13, shown in Fig. 3. A circuit comprising the coil 14 of the reset magnet 11 extends from the positive line conductor 15, through the 15 control switch 16, when the latter is in its left-hand position, conductor 17, switch 13, interlock contact members 6 and 8, resistor 19 and coil 14, to the negative conductor 21. The adjustable resistor 19 determines the 20 degree of energization of the magnet 11.

The main motor circuit extends from trolley conductor 15, through controller 22, conductor 23, overload relay coil 2 and motor armature 25 to the ground. When the 25 circuits, as traced, are energized, coils 14 and 2 exert opposing forces upon the relay armature 3. The armature 3 operates upon the occurrence of a predetermined overload 30 value of the current traversing the motor circuit. The plunger 4 is lifted by the armature 3 to disengage the interlock members 6 and 8 and thereby open the circuit of coil 14.

After the overload relay has operated, it 35 may be restored by actuating the control switch 16 to the right to establish a circuit from the positive line conductor 15, through the control switch 16, conductor 26, resistor 19 and coil 14 to the negative line conductor 21. Armature 12 is attracted by the magnet 14 and causes the trigger 9 to disengage 40 armature 3, which resumes its initial position, indicated by dotted lines.

After the car has passed over the grade, switch 13 is opened and coil 14 is no longer 45 energized.

It is evident that I have disclosed a simple 50 overload mechanism capable of operation under both normal and abnormal conditions and have eliminated the necessity of manually adjusting the overload mechanism. I have also made use of the necessary reset magnet to accomplish the desired results without materially adding to the cost or complicating the relay construction.

55 I claim as my invention:

1. In control apparatus, in combination, a contact member disposed for movement, a coil for actuating the contact member, said coil being adapted to function when energized by a predetermined current, means for locking the contact member in a predetermined position, means for releasing the contact member and means for utilizing the releasing means to oppose the actuation of 60 the contact member by said coil.

2. In control apparatus, in combination, a contact member disposed for movement, a coil for actuating the contact member, said coil being adapted to function when energized by a predetermined current, means for locking the contact member in a predetermined position, means for releasing the contact member and means for utilizing the releasing means to oppose the actuation of the contact member by said coil, and means for varying the opposition offered by the releasing means to the actuation of the contact member by the coil.

3. In control apparatus, in combination, a contact member disposed for movement, a coil for actuating the contact member, said coil being adapted to function when energized by a predetermined current, means for locking the contact member in a predetermined position, an electromagnet for releasing the contact member and means for utilizing the electromagnet to oppose the operation of the contact member by the coil.

4. The combination with an overload relay comprising a movable member and a series 90 coil for actuating said member at a predetermined value, of a latching mechanism for said relay, and electro-responsive means for controlling said mechanism, said electro-responsive means energizing a flux path for 95 varying the predetermined value at which said movable member shall be actuated.

5. In a device of the character described 100 for controlling electrical circuits, in combination, a relay operable to effect the making and breaking of circuits, said relay being adapted to operate upon the flow of a predetermined current, means for opposing the operation of the relay to vary the current value at which the relay will operate, said 105 means being variable in effect thereby to provide for the operation of the relay at different current values, and means for locking the relay in the position assumed when energized.

6. In control apparatus for controlling 110 electrical circuits, in combination, a relay provided with switching means for making and breaking electrical circuits, an armature operated upon the energization of the 115 relay by the flow of a predetermined current, said armature being disposed to operate said switching means, means for locking the switching means in a predetermined position, an electromagnet for releasing said switching means, and means for utilizing said electromagnet to oppose the operation of the armature to vary the current value at which the relay operates.

7. In control apparatus for controlling 120 electrical circuits, in combination, a relay provided with switching means for making and breaking electrical circuits, an armature operated by the energization of the 125 relay by the flow of a predetermined current,

said armature being disposed to operate said switching means, means for locking the switching means in a predetermined position, an electromagnet for releasing the switching means, and means for utilizing said electromagnet for opposing the operation of the armature to vary the current

value at which the relay operates, and means for varying the energization of the electromagnet.

In testimony whereof, I have hereunto subscribed my name this 13th day of December, 1920.

HOWARD H. JOHNSTON.
